UNITED STATES PATENT OFFICE.

LOUIS FERRARA, OF MASPETH, NEW YORK.

SANDPAPER AND RUBBING MACHINE.

Application filed August 15, 1924. Serial No. 732,166.

This invention relates to a machine for use in sandpapering floors, automobile bodies, cabinet walls, or other surfaces, the invention having for an object the provision 5 of a novel machine of this sort which is readily manipulable by hand and in which the active operative element is in the form of a reciprocable device.

For further comprehension of the invention, and of the objects and advantages thereof, reference will be had to the following description and accompanying drawing, and to the appended claims in which the various novel features of the invention are 15 more particularly set forth.

Fig. 1 of the drawing is a side view of my improved sandpapering machine.

Fig. 2 is an end view thereof.

Fig. 3 is a detail horizontal sectional view 20 taken on the line 3—3 of Fig. 1.

Fig. 4 is a detail horizontal sectional view taken on the line 4—4 of Fig. 1.

Fig. 5 is a fragmentary side view showing a slightly modified construction.

In the drawing the reference numeral 10 indicates a small electric motor of ordinary type to the casing of which a projecting handle 11 is attached. Upon one end of the shaft 12 of the motor a gear pinion 13 is fixed, this pinion meshing with a gear 14 loose on a stub shaft 15 fixed upon the end of the motor casing. Fixed to the face of the gear 14 eccentrically thereof, is a pin 16 that engages in a longitudinal slot 17 in an oscillatory lever 18 that is fulcrumed at its upper end to a projection from a housing 19 that is screwed onto the casing.

Upon the lower end of the lever 18 is fixed a foot 20 of rectangular shape in plan view and whose lower surface is curved concentric with the fulcrum point of the lever. Mounted in suitable bearing members 21 at opposite ends of this foot are the drums 22 over which are passed the ends of a web 23 of sandpaper, the web of paper passing under the foot from one drum to the other. The paper is locked to the foot by means of the clamping bars 25 that project across the ends of the foot and are fixed to the 50 ends of the bars 26 slidable in bearing elements 27 in the foot, springs 28 acting to keep the clamping bars in operative position. The foot is formed with a recess 20' in which these parts are located. The inner or adjacent ends of the bars 26 are provided with transverse members 30 between

which is positioned a cam 31 that is fixed on the lower end of a rod 32 that extends upward through a suitable longitudinal boring in the lever 18 and is partially rotatable 60 in the latter. This rod 32 has fixed thereto adjacent its upper end, a laterally projecting pin 34 that is adapted to engage suitable fixed parts when the lever reaches each end of its oscillatory movement, to rock the rod and so momentarily free the clamping bars from the paper to permit of the latter being advanced. These fixed members that the pin 34 engages are here in the form of vertical shoulders 35 on the housing 19 that is threaded on the end of the motor and which covers the gear 14 and the upper end of the lever 18. Fixed to the rod 32, just above the foot 20, is an arm 40 that is adapted 65 to engage one end of a thrust bar 41 slidably mounted on top of the foot, and normally urged in one direction by spring 41^a, this bar having a spring pawl 42 on its other end that bears on a ratchet wheel 43 permitted to turn in one direction only by 70 means of ratchet 43^a operated by spring 43^b, said ratchet wheel being fixed co-axially to one of the drums 22. The pin 34 and arm 40 are so positioned with respect to one another that the clamping bars 25 will be 75 lifted from the paper before the thrust element 41 is engaged to move the drum and advance the paper, the bars 25 again engaging the paper after the said movement of the drum has been completed. The member 41 may be suitably guided as by the pins 45 engaging in a longitudinal slot 46 in said member.

It is believed that the manner of operation and use of my improved sandpapering machine will be readily understood from the above description, it being apparent that the rotation of the motor shaft will cause the foot 20 to oscillate and the paper to be gradually fed forward. The pin 34 in the bar 18 striking the right-hand shoulder 35 turns said bar 18 to the left causing arm 40 to press pawl 42 against ratchet wheel advancing sandpaper, and as previously explained also causes with correct timing to release 25, while when said pin strikes the left-hand shoulder 35 it causes bar 32 to turn to the right thereby not turning the wheel therefore not moving the sand paper even though clamping bars release paper as before explained. The user of the machine retains the paper in engagement with surface to be

treated, and with the proper degree of pressure by means of the handle 11.

In Fig. 5 of the drawing I have shown a slightly modified form of operative connection between the gear 14 and the oscillatory lever. In this modified arrangement the lever, indicated at 18' is fulcrumed between its ends as at 50 while a link 51 is connected at one end to the upper end of the lever and at its other end to the gear 14 eccentrically of the latter.

While I have described that my device is operated by a motor, it is understood that shaft 12 may be rotated manually in any suitable manner.

Having thus described my invention, what I claim as new and desire to protect by Letters Patent of the United States is as follows:—

- 20 1. A sandpapering machine comprising an electric motor, a lever fulcrumed on the motor casing, means forming an operative connection between the motor shaft and the lever whereby rotation of the said shaft oscillates the said lever, and a sandpaper-holding foot on said lever, a pair of drums on said foot, a web of sandpaper engaged at its ends with said drums, means for clamping said sandpaper and means for imparting a rotary step by step movement to the said drums as the said lever oscillates, including a rod extending longitudinally through the lever, a pin projecting from said rod and adapted to engage fixed parts as the lever reaches the ends of its oscillatory movement, an arm projecting from said rod, and an operative connection between said arm and one of said drums, said operative connection comprising a ratchet wheel fixed to said drum, a thrust bar adapted to be engaged by said arm, and a pawl on said thrust bar engaging said ratchet wheel.
- 25 2. A sandpapering machine comprising an electric motor, a lever fulcrumed on the mo-

tor casing, means forming an operative connection between the motor shaft and the lever whereby rotation of the said shaft oscillates the said lever, and a sandpaper-holding foot on said lever, a pair of drums on said foot, a web of sandpaper engaged with said drums, a pair of clamping elements engaged with said sandpaper to retain the latter fixed on said foot, means adapted for operation by oscillation of said lever for momentarily freeing said clamping bars from said paper, and means for imparting an advancing movement to the said drums when the said clamping bars are freed.

3. A sandpapering machine comprising an electric motor, a lever fulcrumed on the motor casing, means forming an operative connection between the motor shaft and the lever whereby rotation of the said shaft oscillates the said lever, and a sandpaper holding foot on said lever, a pair of drums on said foot, a web of sandpaper engaged at its ends with said drums and passing under said foot, a pair of clamping bars holding said paper rigid on said foot, a rod extending longitudinally in the lever and adapted for turning on its own axis, a pin projecting from said rod and adapted to engage fixed parts to turn the rod as the lever reaches the ends of its oscillatory movement, a cam on said rod adapted to lift the said clamping bars from the sandpaper, springs engaged with said bars and holding the latter in operative position, and an arm projecting from said rod operatively connected to one of the drums whereby the latter is given an advancing movement transmitted also to the other of said drums by the intervening paper, timed to take place when said cam lifts said clamping rods.

In testimony whereof I have affixed my signature.

LOUIS FERRARA.
